UNITED STATES PATENT OFFICE.

CHARLES E. F. AHLIM, OF CLEVELAND, OHIO.

DYNAMO-ELECTRIC MACHINE.

1,074,338.

Specification of Letters Patent.

Patented Sept. 30, 1913.

Original application filed February 14, 1910, Serial No. 543,736. Divided and this application filed January 23, 1911. Serial No. 604,120.

To all whom it may concern:

Be it known that I, CHARLES E. F. AHLIM, a citizen of the United States, residing at Cleveland, in the county of Cuyahoga and State of Ohio, have invented a certain new and useful Improvement in Dynamo-Electric Machines, of which the following is a full, clear, and exact description, reference being had to the accompanying drawings.

10 My application No. 543,736, filed February 14, 1910 (of which this is a division) shows and describes a dynamo electric machine operating with a constant potential for varying speeds—a machine as a generator giving a current of constant potential for varying speeds, though receiving current of a constant potential. A characteristic of the machine is that there is a single armature under the influence of two magnet fields, one of which is constant and the other of which increases in strength with the speed. The windings, circuits and connections by which this is accomplished, or, what may be called the electric features of the machine are claimed in the parent application referred to.

15 The present application relates to the mechanical features by which such dynamo electric machine may be constructed as an efficient piece of mechanism.

20 The drawings show a dynamo electric machine of the two pole type embodying this invention.

25 Figure 1 is a vertical longitudinal section through the machine; Fig. 2 is a transverse vertical section of the same; Fig. 3 is a horizontal longitudinal section, omitting the armature with its shaft and commutator and bearings; Fig. 4 is a vertical transverse section through the machine adjacent to the commutator brushes; Fig. 5 is an end view on a reduced scale; Fig. 6 is a diagram illustrating the electromagnetic operation.

30 The main frame of the machine, designated 40, consists of a hollow, barrel-like, iron casting extending above and below the armature and forming also a portion of the ends of the machine, these end portions being annular, as shown at 41 and 42. The 35 annular portion 42 is connected with the main portion 40 by a sleeve-like portion 43 nearer the axis and an outwardly extending annular portion 44. Centrally mounted on the end portions 41 and 42 are disk-like members 45 and 46, preferably of some non-

magnetic material, as brass or aluminum, and shown as removably secured by screws 52. In these end disks 45 and 46, is mounted the armature shaft 47, the mounting being in suitable ball bearings, as shown. The 40 frame openings which the disks occupy are large enough so that the removal of either disk allows the armature to be drawn out of that end of the machine. The casting 40 may be flattened on its outside, above and 45 below the armature, as shown, thereby providing suitable bases on either of which the frame may stand. Figs. 1 and 2 omit the armature winding but show the shaft 47 and the core 48, which may be a laminated structure of disks, or otherwise constructed, as desired. It is shown as composed of members surrounding the shaft and held in place by suitable flanged fittings 49 and 50 on the shaft. The windings, as will be understood, 50 occupy notches 51 in the core.

55 53 designates the commutator bars insulatingly carried by a commutator core 54 on the shaft and locked in place by a nut 55 screwing on to that core against a collar 56 thereon. Beyond the commutator core on one end and beyond the flange 50 on the other, are suitable distance sleeves 58 and 59 and beyond these are the ball bearings referred to. The ball bearing, in the form 60 shown, consists of a ring 60 surrounding the shaft and abutting the distance sleeve, balls 62, and an outer ring 63 seated in the disk member 45 and 46, there being a distance sleeve 61 on the shaft for holding the 65 ring 60 in place. A suitable dust-cap is provided by the disk 65 threaded in place and held by a pin 67 as will be well understood.

are out of any substantial magnetic connection therewith. The cores of these magnets are designated 75. They have flared pole faces 76 and are connected at their outer ends to the iron connecting bar 77 by screws 78. This connecting bar 77 is shown as carried by screw bolts 79 on a cap-plate 80 which may be made of aluminum or other non-magnetic material. If desired, the cap-plate may be made separately and the connecting bar 77 secured to the main frame, either through interposed non-magnetic material or material of small enough cross-section so that the magnetic flux will not be sufficient to interfere with the operation.

Outside of the reduced portion 43 I mount the support for the commutator brushes, consisting of brackets 85 supported on suitable insulation 86 and carrying pivot pins 87 on which are mounted arms 88 carrying the two pairs of brushes, designated 20, 21, and 23, 24. Coiled springs 89 surrounding the pivot pins 87 tend to keep the brushes on the commutator. The brushes projecting freely through openings 84 in the frame portion 43. The brushes are covered by a removable sleeve-like cover plate 90 resting on the main frame and secured to the frame portion 42 by screws 91. This makes a very simple construction and one allowing easy access to the brushes. For the sake of completeness, I will now describe the electromagnetic operation of the machine, as illustrated more particularly in the diagram of Fig. 6. In this diagram the windings J and F are main-field windings corresponding to the winding 82 of Fig. 2, while the double bucker field windings L, H and M D on the poles 70 correspond to the winding 72 of Fig. 1. The armature illustrated is wound as for an ordinary two-pole machine, being connected to successive commutator bars, on the closed circuit principle, as is well understood. The two poles 70 are, of course, of opposite polarity and the horse-shoes 75 are so placed that those of their poles which are adjacent to the poles 70 have a polarity opposite thereto respectively. Thus, as shown in the drawings, the upper pole 70, for example, in the operation of the machine, is a north pole; the upper pole of the right hand horse-shoe 75 a south pole, and so on,—this polarity being indicated by the designating letters N and S on the diagram. 20 and 21 indicate two commutator brushes related to the main field, and 23 and 24 indicate commutator brushes related to the bucker field. The shunt winding of the main field, shown, is in series with a small coil, indicated by D and H, constituting a portion of the bucker field and acting as a teaser thereon, the principal bucker field windings being independent of the main field windings, as hereinafter described.

Referring to the circuits shown in Fig. 6, the letters A and B indicate the main lines. Starting from the lead A, or from the commutator brush 21, the main field winding and the teaser winding may be traced as follows:—via the line C to a few turns D (teaser coil) around the core 70, thence via the line E to a winding F (main field) on the cores 75, thence via the line G to the teaser coil H on the other core 70, thence via the line I to the main field-winding J, thence via the line K to the brush 20. It will be observed that the relative direction of the main coils and teaser coils is such that if a current be flowing to give the main poles the polarity designated, the teaser coils will give the bucker poles a polarity opposite to the adjacent main poles, as also designated. The winding of the main portion of the bucker field starts from the brush 23 through the coil L to the line O and through the coil M to the brush 24, and these coils are of high resistance, and are wound in the same direction as the teaser coils. The lines of force of the two fields are illustrated by the conventional broken lines with arrow heads thereon.

As shown in Fig. 6, T represents a battery in a shunt across the main leads A and B. U represents an automatic switch adapted to control the main line and having a compound winding; one winding of this switch being in a shunt V across the leads A and B, and the other winding W in series in one of the leads, as the lead A. Y indicates an armature under the influence of this compound winding W and X which is adapted, when attracted, to close the break in the lead A between the switch and battery.

Let us assume that the machine is a generator and that the armature is connected with an axle of the car, for example, and that the switch is wound to pick up its armature when a certain current is generated, say that resulting from a train speed of fifteen miles per hour. Now, as the train starts, the armatures rotate slowly and the main line is open at the switch Y so that the voltage builds up in the shunt V through the winding U of the switch. During this period, before the switch picks up, the main field and the bucker field (due to the direction given by the teaser) are operating to give currents of such direction as to cause the successive poles to have opposite signs. The actual direction of this current depends on the residual magnetism, but their relative direction is thus fixed. The bucker field current (due to the high resistance of its winding) is so small in the early stage of rotation as to be negligible. As soon, however, as the switch picks up its armature, thereby throwing the battery on to the line, the counter-electromotive force of the bat-

terry establishes a definite direction for the current suitable to the battery, and this current acting on the winding of the main field and the teaser windings of the bucker field 5 while it may reserve their original polarities (if necessary) will continue their relative polarities. Now, as the speed increases, the main field voltage rises proportional to the speed, inasmuch as this field has a constant excitation, initially, at least, due to the 10 battery, while the voltage of the local bucker field also rises proportional to the speed, being connected solely in series with the armature and thus having an excitation varying with the speed (the constant excitation by 15 the teaser being negligible), and as the effects of these two fields are opposite, the main line current, given out by the machine, is the difference between the main field voltage and the bucker field voltage, which is a constant irrespective of the speed. With 20 the generator, connected as described, when the battery has been fully charged, the counter-electro-motive force thereof, through the switch winding W, now counter-acting the winding X, neutralizes the latter, causing the switch to drop its armature and disconnect the battery, leaving the train lighted solely by the battery. 25

From the above description it will be seen that the skeleton of this machine is designed to carry proper windings for giving the desired constant potential. The peculiarities 30 of the frame, the arrangement and support of the magnet cores, the support for the armature shaft, the holders for the commutator brushes, and the removable caps over such holders all contribute to the efficiency 35 of the machine. These features are covered in this application. When associated with the windings and circuits claimed in my parent application referred to, a simple and effective constant potential generator or motor is provided. 40

Having thus described my invention, what I claim is:—

1. In a dynamo electric machine, the combination, with an armature, of a frame forming a magnetic ring in planes parallel with the plane in which the axis of the armature lies, said frame being open on the sides of the armature, pole pieces carried by such main longitudinal ring, additional pole pieces at the open sides with a different magnetic circuit from the pole pieces first mentioned, and means for supporting the additional pole pieces. 50

2. In a dynamo electric machine, the combination, with an armature and field magnets, of a magnetic ring connecting the field magnets and carrying the magnetic flux through the frame of the machine longitudinally of the armature and having side openings, at least one of the ends of the 55 frame having an opening sufficient for the

removal of the armature, a bearing carried by such end at such end opening, independent magnets at the sides, and means carried by the magnetic ring for supporting such magnets at the sides. 70

3. The combination of a barrel-like frame formed with open sides and ends with central openings in them, an armature mounted within said barrel and having its shaft occupying said openings, removable end members in which the armature shaft is journaled and which are mounted on the frame at said openings, pole pieces carried by said frame, additional pole pieces at the open sides and independent of the full influence of magnetic flux through the barrel-like frame, and means for supporting the additional pole pieces. 75

4. The combination of a barrel-like frame formed with open sides, an armature mounted axially within said frame, removable end members in which the armature shaft is journaled, pole pieces carried by said frame, other pole pieces carried at such open sides, and means for supporting the last mentioned pole pieces and removably closing the sides. 80

5. In a dynamo electric machine, the combination of a main frame, a shaft journaled therein, an armature on the shaft, pole pieces carried by the frame coöperating with the armature, said pole pieces being magnetically connected through the end portions of the frame, a plurality of pairs of additional pole pieces, each pair having a connecting bar of magnetic material independent of the main magnetic flux of said frame, and non-magnetic members carrying said additional pole pieces and forming caps for the sides of the frame. 95

6. The combination, with an armature, of pole pieces, a frame for the machine extending beyond the ends of the armature and supporting the armature shaft, said frame carrying the magnetic flux of the pole pieces mentioned, additional pole pieces coöperating with the armature, and removable side members carrying such additional pole pieces and mounted on the frame. 105

7. In a dynamo electric machine, the combination, with an armature, its shaft and commutator, of an integral frame adapted to contain the armature and commutator and having annular end portions beyond the armature and commutator ends, a pair of central end members carried by the frame, the shaft for the armature being journaled in said end members, the frame being of reduced diameter around the commutator, brush holders comprising brackets mounted on the outer sides of such reduced portion and arms pivoted to the brackets, there being openings through the reduced portion through which brushes carried by the said arms of the holders are adapted to extend into contact with the commutator, and pole 110 115 120 125 130

pieces carried by said frame and having their magnetic flux carried by said annular end portions of the frame.

8. In a dynamo electric machine, the combination, with an armature, of a frame therefor carrying pole pieces, an armature shaft, a commutator thereon, said frame approaching the shaft adjacent to the commutator and being substantially cylindrical
5 and of reduced diameter about the commutator and flanging outwardly at the outer end of the reduced portion, brush holders mounted on the outer face of such reduced portion of the frame, there being openings

through the reduced portion through which 15 brushes carried by the holders are adapted to extend into contact with the commutator, and a sleeve-like cap for said brush holders removably secured to the frame in engagement with the body thereof and with such 20 outwardly flanged portion.

In testimony whereof, I hereunto affix my signature in the presence of two witnesses:
